[57] CLAIM

The ornamental design for a car table, as shown and described.

DESCRIPTION

FIG. 1 is a perspective view of a car table which illustrates my new design;

FIG. 2 is a right side elevational view thereof;

FIG. 3 is a top plan view thereof;

FIG. 4 is a front elevational view thereof;

FIG. 5 is a rear elevational view thereof;

FIG. 6 is a left side elevational view thereof;

FIG. 7 is a perspective view of a car table which illustrates a first alternative embodiment of my new design;

FIG. 8 is a right side elevational view thereof;

FIG. 9 is a top plan view thereof;

FIG. 10 is a front elevational view thereof;

FIG. 11 is a rear elevational view thereof;

FIG. 12 is a left side elevational view thereof;

FIG. 13 is a perspective view of a car table which illustrates a second alternative embodiment of my new design;

FIG. 14 is a right side elevational view thereof;

FIG. 15 is a top plan view thereof;

FIG. 16 is a front elevational view thereof;

FIG. 17 is a rear elevational view thereof;

FIG. 18 is a left side elevational view thereof;

FIG. 19 is a perspective view of a car table which illustrates a third alternative embodiment of my new design;

FIG. 20 is a right side elevational view thereof;

FIG. 21 is a top plan view thereof;

FIG. 22 is a front elevational view thereof;

FIG. 23 is a rear elevational view thereof; and,

FIG. 24 is a left side elevational view thereof.

The underside of my car table is not ornamented.
